UNITED STATES PATENT OFFICE.

EDWARD F. LINDSAY, OF PRINGLE, SOUTH DAKOTA.

SUPPORT AND INSULATOR.

942,086.

Specification of Letters Patent. Patented Dec. 7, 1909.

Application filed April 10, 1909. Serial No. 489,060.

To all whom it may concern:

Be it known that I, EDWARD F. LINDSAY, a citizen of the United States, residing at Pringle, in the county of Custer and State 5 of South Dakota, have invented certain new and useful Improvements in Supports and Insulators, of which the following is a specification.

This invention relates to certain new and 10 useful improvements in insulators for electric conductors.

The main object of my invention is to provide a divided support and insulator for electric conductors.

15 Another object is to provide a separable supporter for electric conductors, so constructed that the insulator proper will be incased and shielded.

A still further object of my invention is, 20 to provide a support for electric conductors, arranged to hold the conductor without tie wires, and prevent their slipping while suspended.

With these and other objects in view, the 25 present invention consists in the combination and arrangement of parts as will be hereinafter more fully described and particularly pointed out in the appended claims, it being understood that changes in the 30 specific structure shown and described may be made within the scope of the claims without departing from the spirit of the invention.

In the drawings forming a part of this 35 specification, and in which like numerals of reference indicate similar parts in the several views, Figure 1 is a perspective view of a separable insulator embodying my invention, Fig. 2 is a sectional view on line 2—2 40 of Fig. 1. Fig. 3 is an end view, Fig. 4 is a face view of the holding member, Fig. 5 is a face view of the held member, Fig. 6 shows the insulator secured to the cross-tree of a telegraph pole, Fig. 7 shows the insulator 45 secured to the side of a building, and used as a supporting bracket.

The aim of my invention is to provide a cheaply constructed readily attachable holder and insulator for electric conductors so constructed that the conductors may be readily secured or replaced, and which is especially adapted to be fastened on vertical surfaces.

In the drawings, 5 represents the main section of the casing as used in my invention, 55 which has the beveled forwardly extending end 6, provided with the beveled under face

7. This section is in the form of a centrally channelled block of wood or other suitable material and has the two oppositely positioned sides 8 which have their inwardly 60 positioned faces undercut as shown in Fig. 3. The bevel faces 9 form in effect a dovetailed groove within which is slidably held the concaved insulator 10. This concaved insulator has its opposite longitudinal edges 65 11, which run parallel with the concaved face 9, beveled as clearly disclosed in Fig. 3, so that the insulator which is made of glass or other insulating material will readily slide within the holder 5 in which 70 it is frictionally held. The beveled sides 8, of the holder 5 at opposite points are provided with the recesses 13, while the glass female insulator 10 is provided with the transversely positioned wire receiving groove 75 15, which registers with the recesses 13. The holder 5 may be made of wood, fiber, metal or any other suitable material.

Held upon the sides 8, 8 and against the bevel under face 7, of the holder 5 is the cap 80 plate 16, which forms a held member. This member 16 is of a size to snugly fit upon the holder 5 as disclosed in Fig. 1. The projection 6 forms the top of the holder when secured to support a conductor and overlapping the upper beveled end of the member 16 prevents any water creeping down between these two holding members. This cap plate 16 also has its inner edges 17 beveled, to slidably receive the male insulator 90 20 having the convex face 21 which is also traversed by a wire receiving groove 22 registering with the groove 15. These grooves 15 and 22 are of such a size as to snugly receive the conductor. The sides of the cap 95 plate are recessed at opposite points as shown at 25, these recesses 25 registering with those marked 13 within the holder 5 as shown. Both of the glass insulators are arranged to be frictionally held within the casing 100 forming shielding holders.

The idea of incasing the insulators forms an important part of my invention as it prevents mischievous parties from breaking the same while at the same time preventing any 105 water, ice or snow covering them and forming a circuit with the conductor held by these insulators. The top plate is also made of wood, compressed fiber, or any other suitable material. The holding member 5 is secured by means of a nail A which is driven through the upper projecting end 6 of the

holder to securely support the same. The held member after being secured to the holding member is fastened by means of a suitable nail or screw B which is directed 5 through the end of both of the holders to securely support the same. In replacing the conductor it is simply necessary to remove the nail or screw B when the face plate 16 may be removed with its connected insulator.

As shown each glass insulator has its two opposite positioned longitudinal edges provided with the flat upper shoulders a, a, which the wire receiving grooves extend. 15 The concave as well as the convex faces of these glass insulators continue abruptly from these meeting shoulders a as shown in Fig. 3.

From the foregoing it will be seen that I have an incased insulator made in two separable sections between which the conductor is held against slipping, and from which the conductor can be readily removed. The lower supporting screw or nail B may also be made to do service in supporting the two 25 glass insulating members, should these members in any way become loosened between the holders, though care must be taken that these insulators will not slip down so far that the conductor will contact with the 30 holder and holding members which are not made of insulating material.

Having thus described my said invention, what I claim as new and desire to secure by United States Letters Patent is:

35 1. A holding member having an extending upper end provided with a beveled under face, two oppositely positioned beveled edges, of a non-conductor having a concaved face and two beveled faces running parallel 40 with said face and frictionally held within said holding member, a cap plate having oppositely positioned bevel edges and an up-

per beveled end resting below said extending end, and a beveled edged non-conductor having a convex face registering with said concave face and slidably held to said cap plate, each of said non-conductors having a transversely positioned wire receiving groove.

2. In combination, a holding member having beveled edges, a held member having beveled edges secured to said holding member, each of said beveled edges having a recess, a concave beveled edge insulator held within said holding member, a bevel edged insulator having a convex face held within said held member, each of said insulators having a transversely positioned groove and means to secure said held member to said holding member.

3. A holding member having an extending upper end provided with beveled under face and two oppositely positioned beveled edges, of a non-conductor having a concaved face provided with two oppositely flat shoulders, the longitudinal edges of said insulator being beveled edged, a wire receiving slot traversing the concaved face of said insulator, a held member having oppositely positioned beveled edges and an upper beveled end resting below said extending end, 60 and a beveled edged non-conductor having a convex face registering with said concave face and two oppositely positioned flat shoulders 65 said insulator being slidably held within said held member, each of said members 70 having a transversely positioned recess, and means to secure said members.

In testimony whereof I affix my signature in presence of two witnesses.

EDWARD F. LINDSAY.
